UNITED STATES PATENT OFFICE.

MAX K. KASMAR, OF CHICAGO, ILLINOIS.

PROPELLING AND STEERING STRUCTURE FOR AEROPLANES, BALLOONS, KITES, &c.

1,069,880.

Specification of Letters Patent. Patented Aug. 12, 1913.

Application filed March 8, 1909. Serial No. 481,887.

To all whom it may concern:

Be it known that I, MAX K. KASMAR, a citizen of the United States, and a resident of Chicago, in the county of Cook and State of Illinois, have invented certain new and useful Improvements in Propelling and Steering Structures for Aeroplanes, Balloons, Kites, &c., of which the following is a full, clear, and exact specification.

10 The object of my invention, broadly stated, is to impart to the vanes of a propelling and steering structure a movement and movements by which the vanes exert a positive vertical downward pressure upon 15 the atmosphere with reference to the earth's surface and also an oblique pressure relative to the same surface whereby aeroplanes, balloons, etc., are bodily lifted and may be directed, propelled and steered in varying 20 upward and downward inclined planes with reference to the earth's surface.

A further object is to provide means by 25 which said vanes may be conveniently shifted from a horizontal position to various inclined positions and relative to the direction 30 of the force which they exert upon the atmosphere and may be maintained in any of these positions at will, whereby the direction of movement of aeroplanes and balloons may be maintained and varied at will.

With these ends in view, my invention consists in certain features of novelty in the construction, combination and arrangement of parts, by which the said objects and certain other objects hereinafter appearing are attained, all as fully described with reference to the accompanying drawings and more particularly pointed out in the claims.

In the said drawings: Figure 1 indicates 40 a side elevation partly in section on the line 1—1 Fig. 4 of a propelling and steering structure containing my invention with the vanes adjusted to exert substantially a pressure upon the atmosphere in a vertical direction with reference to the earth's surface. Fig. 2 is a perspective view of one of the vanes detached. Fig. 3 an enlarged detail longitudinal view of the power shaft of the vanes on the line 3—3 Fig. 5 showing in 50 transverse section the means employed by which the vanes are bodily rotated by the power shaft and shifted upon their individual axes. Fig. 4 is an end elevation of the structure shown in Fig. 1. Fig. 5 an enlarged top plan view partly in section showing the devices employed for shifting the

vanes upon their individual axes. Fig. 6 is a detailed end elevation of a propelling and steering structure containing a modified form of my invention. Fig. 7 a perspective 60 of one of the vanes detached showing valves for reducing the resistance of the vanes to the air in their ascending movement by their common axes. Fig. 8 is a detailed front elevation of a modified form of the vanes and the means by which they are secured to their common axes of revolution. Fig. 9 a detailed view of a modified form of the mechanism employed for shifting the vanes upon their individual axes to vary their inclination. Fig. 10 a detailed sectional view 70 showing a modified form of a means by which the vanes may be connected with the eccentric or other means for shifting them on their individual axes, and Fig. 11 is a longitudinal section of a modified form of one of the vanes.

Similar numerals of reference indicate the same parts in the several figures of the drawings.

12 indicates one of two inverted V-shaped up-rights secured by bolts 13 to any suitable part of the framework (not shown) of an aeroplane, balloon, etc., in which up-rights is journaled a power shaft 14, rigidly secured to which by a key 15 is a hub 16 from which project a number of radial arms 17, four in number as shown in Fig. 1, but which may be of any desired number greater or less, the power shaft (see Fig. 4) being 90 provided with a pulley 18 connected by a belt (not shown) to any suitable motor or other driving power.

Mounted on each radial arm and connected thereto by a shaft 19 is a vane 20 which is rigidly secured to the shaft by means of bars 21 (see Figs. 4 and 6) and bolts 22, these bars being provided with depending lugs 23 at a point about the center of length of the vanes, the hubs of which are 100 keyed or otherwise secured to the shaft 19.

Shaft 19 is journaled in the oppositely arranged radial arms 17 (see Fig. 4) and has one end projecting outside thereof on which is secured (see Figs. 1 and 4) a lug 24 provided toward its free end with a perforation 25 in which is loosely secured the upper end of a rod 26, the lower end of which (see Fig. 3) terminates in a cross-bar 27 projecting beyond both the inner and outer sides 110 of the rod and which has its ends projecting respectively into an eccentric groove 28 in a

plate 29 and into radial grooves 30 in a short arm 31 secured to a hub 32 (see Fig. 3) which together with the long radial arm 17 is secured to the shaft 14 by a key 33.

5 The eccentric 29 is sleeved upon the shaft 14 and has secured to its outer face a sprocket wheel 34 adapted to be actuated by a drive chain (not shown) connected with some suitable power, as for instance a steering lever, so that by shifting the eccentric on its axis, the vanes through their rod connection therewith may be adjusted to any desired inclination or maintained in a horizontal position throughout their rotation by 10 the power shaft for purposes hereinafter more fully described, the short arm 31 serving to maintain the inner end of the connecting rod 26 of the vane from vibration and therefore fixed for the time being in its 15 adjusted position in the eccentric groove, the grooves in the short arm 31 being on lines radiating from the axis of the power shaft 14 around which they revolve.

The drawings illustrate the employment 20 of four vanes mounted upon as many radial arms secured to the power shaft, but there may be a greater or less number of vanes as desired or required, and the vanes 20 which may be of light thin sheet metal or 25 any other material adapted for the purpose are, as illustrated in Figs. 2 and 4, V-shaped in cross section and preferably with a greater spread to the V at their outer end 35 than at their inner end 36, so that 30 in side elevation as will be seen in Fig. 1 their apices incline downwardly with reference to their bottom edges from their inner toward their forward ends, whereby the vanes deflect the pressure of the air current 35 coming in contact with their under and operative face, and thereby change the angle of force exerted by the atmosphere directed against the underside of the vanes. For example in the position shown in Fig. 1 in 40 which their lower edges lie in a horizontal plane parallel to the earth's surface, air pressure upwardly against the under side of the vanes will be deflected along a line inclining upwardly from the shallower 45 toward the deeper end of the vanes, but if the position of the vanes is shifted so that its apex lies in a horizontal plane, then the pressure will be in a vertical line at a right-angle through the apex along its entire 50 length. The V-shaped form of the vanes serves to increase their resistance to the air on their down stroke, and to decrease their resistance on the up stroke, it being understood that whether they are adjusted, as 55 shown in Fig. 1, or at any other angle they will maintain that position throughout their rotation by their power shaft as will now be explained.

In operation, when the power shaft 14 is 60 revolved in the direction indicated by the

arrow in Fig. 1 there will be produced a rotation of the arm 17 and of the vanes carried by the arm, but owing to the pivot connection between the vanes, the eccentric, although adjustably fixed with reference to the power, will oscillate the vanes upon their individual axis in such a manner that they will maintain the same bodily position uniformly throughout their rotation about the power shaft 14. For example, if a vane 70 starts from the lowest position in Fig. 1 in the direction indicated by the arrow, it will as it is carried upward by the radial arm, have the inner end of its eccentric connecting rod gradually shifted inwardly toward 75 the axis of its rotation, so that the ascending vane will be gradually shifted from a position at right-angles to the arm until by the time the arm has reached a point between 80 its two extremes of movement, the vane will have assumed a position parallel therewith, that is to say, on a line lengthwise through the arm and parallel to the side edge of the vane, but as the arm gradually rises to the 85 limit of the upward movement of the vane, then the vane will continue its shifting movement until when at the end of its upward stroke it again lies at a right angle to its supporting arm 17 for in that position 90 the end of the rod has been moved inwardly 95 to its nearest possible approach to the power shaft 14. As the supporting arm and the vane move downwardly from the limit of their upward stroke, the inner end of the rod 26 is as gradually moved away from 100 the shaft 14, but, as indicated in dotted lines in Fig. 1, the position of the vane relative to the earth's surface is maintained precisely the same as that which it had when 105 it began to move upwardly from its lowest position. In other words, all of the vanes have a planetary movement, that is to say, a continuous revolution about the axis of the power shaft and a revolution in the meantime about their individual axis, the 110 result being that owing to their concave form they exert a downward pressure on the atmosphere during their operation thus exerting a lifting force on the aeroplane, balloon, etc., to which they are attached and 115 offer no substantial resistance to the atmosphere or opposition to their downward pressure during their ascent, because of the peculiar cutting edge form so to speak of their upper, that is to say, their convex surfaces. 120

Assuming the apices of the vanes to have the inclination indicated in Fig. 1, there will be an upward deflection of the air pressure throughout the downstroke of the vanes, the effect of which will be to prevent 125 the air vessel from rising in a vertical line and deflect it upwardly at an oblique angle thereto and thereby impart to it a simultaneous rising and forward movement in an upward inclined direction. If however, by 130

the shifting of the eccentric the apices are maintained on a horizontal line, then the direction of the air pressure exerted by the vanes on their downward movement throughout their length will be on a line vertical to the earth and lift the aeroplane along that line, except so far as it may be deflected by the natural direction of the air currents themselves.

10 On the other hand, if the vanes are adjusted so as to be maintained in a tilted position opposite that which they are indicated to have in Fig. 1, then following the same law the air vessel will be directed on a descending line but with a resistance tending to retard a too rapid descent of the vessel.

15 At this point it is important to observe that with the connection of the eccentric with a steering lever or wheel within convenient reach of the occupant of the air vessel to which my invention is attached, he may shift the angle of the vanes from time to time so as not only to vary the 20 height of the aerial vessel but to deflect it upon varying lines of inclination.

25 From the foregoing it will now be apparent that my invention embraces a structure, the operation of which is three-fold, 30 namely that of propelling, that of steering and that of retarding and increasing the movement of such a vessel.

35 In Figs. 7 and 11 is illustrated a modified form of the vanes 20 in that such vanes are provided with a number of openings in which are valve doors 37 which may be in any number, and which are forced open by air pressure during the ascent of the vanes and closed immediately they commence their 40 descent, said door-like valves being hinged at 38 and, (in Fig. 11) limited in their downward movement by a wire fabric 39 or a number of cross wires forming a grating-like structure.

45 In Fig. 8 is illustrated a modified form of the vanes, as indicated at 40, in which is a vane diamond-like in form as preferred or required, the shaft of said vanes being provided in bifurcated arms 41, which may be 50 cast with or otherwise secured through a hub 42 on the power shaft 14, the vane 40 being actuated through the lug 24 and connecting rod 26 in the same manner as shown in Fig. 1.

55 As illustrated in Fig. 6, the connecting rods, their eccentric and short radial arms may be dispensed with without a departure from my invention as for example, there may be on the individual shafts 19 of the 60 vanes a sprocket wheel actuated so as to change the pitch or inclination of the vanes by means of endless chains 43 connecting sprockets on a line passing through the axis of the power shaft by means of sprockets 65 44, sleeved on the power shaft, that is to

say, in the structure shown three of said sprockets formed integrally with each other, one for each of the endless chains connecting the vane sprocket and the third for a sprocket chain connected to the steering gear for actuating the other two sprockets so as to shift the angle of the vanes.

70 In Fig. 9 I have illustrated a still further modification of my invention which consists in having on the individual shafts 19 of the vanes a bevel gear 45 and a pinion 46 meshing therewith mounted upon a shaft 47 journaled in suitable bearings 48 and 49, secured to the radial arms and provided at its inner end with a beveled pinion 50 meshing with a beveled gear 51 sleeved on the drive shaft 14 and actuated by a sprocket connected with the steering apparatus in the same manner that the sprocket wheel 44 is actuated and for the same purpose.

75 In Fig. 10 is illustrated a modification of the means shown in Fig. 3 for confining the inner ends of and actuating the rod 26, that is to say, the radial groove short arms 31 may be dispensed with and the cross bar of the rods confined between two plates 52 and 53 secured together by a bolt or screw 54 each of which is provided with registering 80 eccentric grooves and are sleeved on the power shaft 14.

85 In operation the movement and adjustability of direction of force of the vanes and the effect of their propelling and adjusting mechanism is precisely the same in the structure shown in Figs. 6, 7, 9 and 11 as in 100 the structure illustrated in Fig. 1, and in this connection it should be observed that notwithstanding their complete and continuous revolution about the power shaft, the force of the vanes during their operation 105 and their adjustment is substantially the same in effect and result as that produced by a flying bird for it rises by exerting a direct vertical pressure as nearly as may be with reference to the earth upon the atmosphere, and it shifts the inclination of its wings to different inclinations as it desires to rise or descend or propel itself in a horizontal plane in substantially the same manner that accrues to the maintaining of the 110 vanes in fixed planes while traversing around a fixed axis and shifting their angles with reference to the earth's surface as hereinbefore described. In other words, the manipulation of the joints of the wings of a 115 bird as employed to propel direct and resist air currents is substantially the same as that produced by the planetary movement and adjustability to differing planes of the vanes of an apparatus containing my invention.

120 Having described my invention what I claim and desire to secure by Letters Patent is:

1. A propelling and steering apparatus for the purpose described, comprising in 130

combination a number of elongated vanes and substantially V-shaped in cross section, means imparting a planetary movement to said vanes and means continuously maintaining the apices of said vanes as the upper surface thereof, substantially as described.

2. A propelling and steering apparatus for the purpose described comprising in combination a number of elongated vanes substantially V-shaped in cross section, and having their apices inclined relative to their edges, and means supporting and actuating said vanes, substantially as described.

3. A propelling and steering apparatus for the purpose described comprising in combination a number of elongated vanes substantially V-shaped in cross section, means imparting a planetary movement to said vanes, and means continuously maintaining the apices of said vanes as the upper surface thereof, substantially as described.

4. A propelling and steering apparatus for the purpose described, comprising in combination a number of vanes V-shaped in cross section and provided with a number of valves opening downwardly, and means for imparting a planetary movement to said vanes whereby their concave inner faces exert a downward pressure upon the atmosphere and said vanes are substantially relieved from resistance to the air in their rising movement, substantially as described.

5. A propelling and steering apparatus for the purpose described, comprising in combination a number of vanes substantially V-shaped in cross section and provided with valves opening downwardly by a pressure varied during the rising movement of said vanes, means for imparting a planetary movement to said vanes and means for varying the bodily angle of said vanes whereby the angle of ascent and descent of an aeroplane or balloon is determined and regulated, substantially as described.

6. A propelling and steering apparatus for the purpose described, comprising in combination a power shaft, radial arms projecting therefrom, vanes pivoted to the outer end of said arms, a combined sprocket and eccentric sleeve upon the power shaft, means for actuating said sprocket, and means connecting said sprocket with the vanes, whereby the shifting of the sprocket upon its axis simultaneously changes the angle of the face of the vanes relative to lines drawn through their axes, substantially as described.

In witness whereof, I have hereunto set my hand and affixed my seal this 22d day of January A. D. 1909

MAX K. KASMAR. [L. s.]

Witnesses:
